UNITED STATES PATENT OFFICE.

WILLIAM BUTTLER, OF RED KEY, INDIANA.

DESIGN FOR SHEET OR PLATE GLASS.

SPECIFICATION forming part of Design No. 28,847, dated June 14, 1898.

Application filed February 17, 1898. Serial No. 670,713. Term of patent 14 years.

To all whom it may concern:

Be it known that I, WILLIAM BUTTLER, of Red Key, in the county of Jay, in the State of Indiana, have invented a new and original 5 Design for Sheet or Plate Glass, of which the following is a full, clear, and exact description, reference being had to the accompanying drawings, forming part of this specification, in which—

10 Figure 1 is a face view of a piece of sheet-glass embodying my design. Fig. 2 is a rear face view, and Fig. 3 is a cross-section, of the sheet.

The design consists in a sheet or plate of 15 glass one face of which is provided with a plain surface, while the other face is rough-

ened and broken up, so as to give a pebbly surface, having projections like the rough or hammered surface of stone.

In the drawings, 2 represents a sheet of 20 glass having one plain smooth face and its other face provided with rough irregular projections 3, like those of a rock face.

I claim—

The design for sheet and plate glass, substantially as herein shown and described.

In testimony whereof I have hereunto set my hand.

WILLIAM BUTTLER.

Witnesses:

GEORGE P. WILSON,
GEORGE B. BLEMMING.
